UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed July 8, 1921, Serial No. 483,361. Renewed January 25, 1926.

The present invention relates in general to automatic telephone systems but is concerned more particularly with such systems in which the toll or long distance connections also are established automatically. The object of the invention may be said to consist in the production of new and improved circuit arrangements whereby the usual cord circuits at the toll operator's position, as well as their corresponding jacks, are entirely eliminated.

The above indicates in general terms the scope of the invention. Various features included in the working of the complete system will not now be specifically mentioned but will be described in the specification which is to follow, and pointed out in the claims.

Of the accompanying drawings to which reference will be made in the specification, Figs. 1 and 2, when arranged in order with corresponding lines at the ends thereof in alignment, represent diagrammatically a toll line extending between two more or less widely separated exchanges in a system embodying the principles of the present invention, together with sufficient of the apparatus in each exchange to enable the invention to be understood. Fig. 3 is a schematic diagram illustrating the general layout of the system.

Referring to Fig. 3, three automatic exchanges are shown which, beginning at the left, will be designated respectively, as the No. 1 exchange, the No. 2 exchange, and the No. 3 exchange. These exchanges are assumed to be located in different cities and, although the exact size is of no great consequence, they are assumed to have a capacity of 10,000 lines each. With the capacity as above noted, local connections are established through the medium of individual line switches or trunk selectors, first selectors, second selectors, and connectors. For example, the subscriber at substation A, in the No. 1 exchange, is able to establish connection with the subscriber at substation A' through the medium of the individual line switch C, first selector E', second selector F, and the connector H. This is the usual percentage trunking system and is mentioned because of the fact that the greater portion thereof comprising the second selectors and connector switches is used also in establishing incoming toll connections.

Each exchange is provided with a toll board presided over by one or more operators who establish all outgoing toll connections. The operators in the No. 1 and the No. 3 exchanges have access to the local subscribers' lines by way of an incoming toll first selector, such as the selector E or the selector E', and thence by way of the regular trunking system. In exchange No. 2, however, the toll operators obtain connection with the subscribers' lines through a separate trunking system which is commonly known as a toll service trunking system. In such a system the circuits of the switches are changed slightly as will be pointed out hereinafter; the connector H', for example, a combination toll and regular connector, acts somewhat differently when used by a toll operator than it does when used by a subscriber. Accordingly an operator in exchange No. 2 extends a connection to a subscriber, the subscriber at substation A', for example, by way of either toll first selector E' or toll first selector E'', toll second selector F', and the combination toll and regular connector H'. It is to be understood of course that the installation of a separate toll service trunking system in any of the three exchanges shown is a matter of choice; however, in the exchanges that have sufficient outgoing toll traffic to warrant the added expense, a toll service trunking system is to be highly recommended because such a trunking system is better suited to the operating requirements and also because of the fact that better transmission is afforded when a toll service trunking system is used than is possible when only the regular trunking system is used.

Proceeding now to the trunking between exchanges, the No. 1 and the No. 2 exchange are interconnected by a group of toll lines sufficient in number to handle the traffic. One of these toll lines is the toll line X. Similarly another group of toll lines, of which the toll line Z is one, connects the No. 2 exchange and the No. 3 exchange. There are no toll lines directly connecting the No. 1 and the No. 3 exchanges and therefore connections between these two points must necessarily be extended by way of the No. 2 exchange.

The toll lines, which heretofore have terminated at each end in the usual manual jacks, terminate in operators' controlling

key circuits instead. The trunk line X, for example, extends from the operator's controlling key circuit O in the exchange No. 1 to the operator's controlling key circuit O' in the exchange No. 2. Similarly the trunk line Z extends from the operator's controlling key circuit O² in the No. 2 exchange to the operator's controlling key circuit O³ in the No. 3 exchange. In addition to terminating in the before mentioned operators' controlling key circuits, the toll lines X and Z terminate at each end in an automatic repeater such as the repeaters D, D', D², and D³ as is clearly shown in the drawings. Each of these repeaters is associated with a first selector such as the selectors E, E³, E⁴, and E⁸. The first nine levels of the banks of these switches are connected in multiple with the first nine levels of the banks of the regular first selectors, as the drawings clearly indicate. Since the toll operators are never required to call the toll recording operator, who is reached by the subscribers by dialling O, there is thus left available for other purposes the tenth level of the toll first selectors. In the No. 2 or intermediate exchange this level is used for through switching and for this purpose a group of toll switching selectors is provided, one of which is indicated by the reference character F². These toll switching selectors are accessible in common to all the incoming toll first selectors in the No. 2 exchange and have common access to all the groups of toll lines terminating in the No. 2 exchange, it being understood of course that there may be a number of such groups, each extending to a different city, in addition to the two groups indicated in Fig. 3. No toll switching selectors are shown in either the No. 1 or the No. 3 exchange. In case there should be a fourth exchange, the No. 3 exchange would take on the character of an intermediate exchange and would be equipped with toll switching selectors in the same manner as the exchange No. 2, and if there should be another exchange similarly located, with respect to the No. 1 exchange, the No. 1 exchange also would take on the character of an intermediate exchange. It is now seen that the incoming toll first selectors in the No. 2 exchange are used not only for completing toll connections to subscribers in that exchange, but are also used in conjunction with the toll switching selectors such as the selector F² for extending through calls from the No. 1 to the No. 3 exchange or to any other exchange that may be connected with exchange No. 2 by toll lines.

To further illustrate the general trunking system, a call may be traced from the substation A² in the No. 2 exchange, to the substation A in the No. 1 exchange. This connection, it may be said, is completed by

the operator in the No. 2 exchange and is extended to the called substation over the following path: the left hand end of the operator's controlling key circuit O', automatic repeater D', trunk line X, automatic repeater D, incoming toll first selector E, second selector F and connector H. The connection to the local subscriber in the exchange No. 2 is set up over the toll service trunking system and when completed may extend over the following path: right hand end of the operator's controlling key circuit O', toll first selector E³, toll second selector F³, and combination toll and regular connector H'. Assuming now that the called subscriber is in the exchange No. 3 instead of the exchange No. 1 the connection to the called subscriber may be set up over the following path: the right hand end of the operator's circuit O², repeater D², trunk line Z, repeater D³, incoming toll first selector E⁸, second selector F⁴, and connector H². In this case the connection to the local subscriber in the exchange No. 2 may be extended over the following path: the left hand end of the operator's circuit O², toll first selector E⁶, toll second selector F⁵, and combination toll and regular connector H'. Assuming, now that the toll operator in exchange No. 1 extends a connection from a substation, the substation A' for example, in exchange No. 1 to a substation in exchange No. 2, the substation A³ for example, she sets up the connection to the called substation over the following path: the right hand end of the operator's controlling key circuit O, repeater D, trunk line X, repeater D', incoming toll first selector E³, second selector F' and connector H'. The connection to the local subscriber at substation A' is set up over the following path: the left hand end of the operator's controlling key circuit O, incoming toll first selector E, second selector F, and connector H. Assuming now that the called substation is a substation in exchange No. 3, the substation A⁴ for example, the connection may be extended over the following path: the right hand end of the operator's circuit O, repeater D, trunk line X, repeater D', incoming toll first selector E³, toll switching selector F², repeater D², toll line Z, repeater D³, incoming toll first selector E⁸, second selector F⁴, and connector H².

Assuming that the toll operator in exchange No. 3 establishes a connection between a substation in the same exchange, the substation A⁵ for example, and a substation in exchange No. 2, the substation A³ for example, she may set up the connection to the latter or called substation over the following path: the left hand end of the operator's controlling key circuit O³, repeater D³, the trunk line Z, repeater D², incoming toll first selector E⁴, regular sec-

ond selector F' , and connector H' . The connection to the local subscriber is extended over the following path: right hand end of the operator's circuit O^3 , incoming toll 5 first selector E^8 , second selector F^4 , and connector H^2 . In case the called subscriber is a subscriber in exchange No. 1, the subscriber at substation A' , for example, the connection to the called substation is set 10 up over the following path: left hand end of the operator's controlling key circuit O^3 , repeater D^3 , toll line Z' , repeater D^2 , incoming toll first selector E^4 , toll switching selector F^2 , repeater D' , toll line X , repeater D , incoming toll first selector E , second selector F , and connector H . It is thought 15 that the foregoing is sufficient to make clear the general layout of the system.

Reference will now be had to the circuit drawings comprising Figs. 1 and 2, for a description of the new apparatus involved. These drawings show diagrammatically all the new circuits associated with a toll line 20 in a system embodying the principles of the invention, which is the system shown schematically in Fig. 3.

The apparatus shown in Fig. 1 is located in the No. 1 exchange, and the apparatus shown in Fig. 2 is located in the No. 2 exchange. It will be noted that the corresponding parts are cross referenced between Figs. 1 and 2 and Fig. 3 so that they are easily located on either. Referring now particularly to Fig. 1 the operator's controlling key circuit O shown therein is very much similar to, and in fact may be practically a duplicate of the cord circuit which would otherwise be used for the same purpose. This controlling key circuit, however, as has been mentioned hereinbefore, unlike a cord circuit has each end permanently associated with a particular trunk line, and consequently is individual thereto instead of being common to a number of trunk lines. As shown, the right hand end of the controlling key circuit O is permanently associated with the right hand end of the repeater D and consequently with the toll line X ; while the left hand end of the key circuit O is associated with the trunk line comprising conductors 93-95 inclusive. The said trunk line is understood to extend to and terminate in an incoming toll first selector such as the selector E , Fig. 3. This selector switch, together with the selectors E' , E^2 , E^3 , E^4 , E^7 , E^8 , F , F' , F^2 , and F^4 , is of the well known vertical and rotary type and the circuit thereof may be the same as that of the selector E^3 , disclosed in the United States patent to Willis No. 1,277,675, granted Sept. 3, 1918. The circuit of each of the connectors H and H^2 to which the selectors F and F^4 , respectively, have access may be the same as the circuit of the con-

nector H shown in the patent referred to. 65 The circuits of the operator's equipment O are shown complete and will be fully described later.

The repeater D in which one end of the toll line X terminates in a two way automatic repeater and is used to translate loop dialling impulses into simplex dialling impulses and vice versa, and for several other purposes which will be more fully pointed out later. The repeater D' , Fig. 2, on the 70 other end of the toll line X and in exchange No. 2 is an exact duplicate of the repeater D but the operator's circuit O' differs from the operator's circuit O in that the right hand or local end thereof, instead of being 75 used for operating switches in the regular trunking system as the local end of the operator's circuit O is designed to do, is used for controlling switches in the previously mentioned toll service trunking system. 80 Reference will now be had to my prior United States patent, No. 1,315,444, granted Sept. 9, 1919, in which Figs. 1, 2 and 3 show a complete connection from a toll operator's 85 position to a called substation by way of a toll service trunking system. The operator's circuit O' , shown in the present drawings, is designed to cooperate with such a toll service trunking system, and accordingly the 90 selectors E^5 and E^6 , shown in Fig. 3, of my present application are assumed to have circuits substantially like that of the selector V' , Fig. 2, of the patent last referred to. Similarly the toll second selector F^3 and the 95 combination toll and regular connector H' shown in the present drawings are assumed to have circuits corresponding respectively to those of the toll second selector W' and the combination toll and regular connector H' which also are shown in the patent last 100 referred to.

In the lower left hand corner of Fig. 2, three bank contacts 190-192, inclusive, are shown. These bank contacts, it may be said, are assumed to be in the bank of a toll switching selector such as the selector F^2 , Fig. 3. It is to be understood that the repeater D in exchange No. 1 would be similarly equipped with normal conductors, which would extend to and terminate in bank contacts of toll switching selectors, if the exchange No. 1 were an intermediate exchange. 115

The apparatus having been described in a somewhat general manner will now be described more specifically in connection with a detailed description of its operation. For this purpose it will be assumed that the subscriber at substation A^3 , Fig. 3, in exchange No. 2 desires to converse with the subscriber at substation A' in exchange No. 1. Upon removing his receiver, the subscriber at substation A^3 is automatically 120 125

connected with a first selector such as the selector E² by his individual line switch or trunk selector C².

The subscriber at substation A³ now dials 5 the digit 0 whereupon the selector E², assuming that this switch has been selected, raises its wipers to the tenth level and rotates them in search of an idle trunk line extending to the toll recording operator. 10 This part of the operation is old, and the apparatus used therein forms no part of the invention, but is pointed out merely because of the fact that it is so closely related with what is to follow. To continue, when the 15 toll recording operator answers she converses with the subscriber at substation A³, and after finding out his number and the number of the subscriber with whom he desires to converse and the exchange in which 20 the latter's line terminates, she may, and we shall assume that she does, make out a ticket containing the necessary information. The recording operator now passes the previously mentioned ticket over to a toll operator in 25 exchange No. 2 and tells the calling subscriber to replace his receiver and wait until he is called by the toll operator. When the subscriber at substation A³ replaces his receiver upon the switchhook the established 30 connection is released.

The toll operator in exchange No. 2, upon the receipt of the before mentioned ticket, throws her key K⁴ into the call out position thereby operating the springs 161-163, 35 inclusive. Spring 163, upon operating, closes a circuit for release relay 172 in series with the resting contact of spring 160 of the release key K³ and said spring. Upon energizing release relay 172, at armatures 177 and 178 places the following bridge across the conductors 193 and 195: from conductor 195 by way of the working contact of armature 178 and said armature, the working contact of spring 162 of key K⁴ and said 40 spring, the secondary or right hand winding of the induction coil associated with the operator's head set, resting contact of spring 166 of key K⁵ and said spring, impulse springs of the calling device S', spring 167 of key K⁵ and its resting contact, spring 161 of key K⁴ and its working contact, and armature 177 and its working contact to conductor 193. As a further result of the energization of relay 172 it places ground on release trunk conductor 194 of the repeater D', at armature 179. This ground potential extends to the test contact 191 and its multiples in the banks of the toll switching selectors thereby causing the trunk line X to test 45 busy to the said toll switching selectors in the usual manner. As a further result of the placing of a ground potential on the release trunk conductor 194 a circuit is closed for the left hand or polarizing winding of the 50 electropolarized supervisory relay 174 of the

operator's circuit O, and also for the upper or polarizing winding of electropolarized relay 111 of the repeater D'. The polarizing winding, however, consisting of a small number of turns of high resistance is not able 55 to energize the relay in either case. As a still further result of the placing of the ground potential on release trunk conductor 194, relay 102 of repeater D' is energized over the following circuit: from ground, 60 by way of release trunk conductor 194, armature 129 of relay 108 and its resting contact, and relay 102 to battery. Relay 102, upon energizing, opens the normally closed bridge across conductors 193 and 195, at armatures 65 113 and 114, and places the upper and lower windings of line relay 104 in bridge of the said conductors instead, the bridge in either case including the right hand windings of 70 repeating coil T'. Line relay 104 immediately energizes over the previously traced bridge across the conductors 193 and 195 in the operator's circuit O' and closes a circuit 75 for the release relay 105, at armature 120. Upon energizing, relay 105 prepares a circuit 80 for relay 106, at armature 122; and closes, at armature 123, a circuit which extends from ground by way of the said armature and its working contact, and the resting contact of armature 108 and said armature, to release trunk conductor 194. By 85 means of this ground on the release trunk conductor, release relay 172 of the operator's circuit O' is maintained energized and the trunk line is kept busy, after the key K⁴ 90 is restored to normal position, which occurs subsequently. As a further result of the energization of line relay 104 it completes, at armature 119, the following circuit for the 95 supervisory relay 109 of repeater D' and line relay 24, of the repeater D. From ground by way of the upper winding of line 100 relay 24 of repeater D, resting contact of armature 32 and said armature, resting contact of armature 30 and said armature, resting contact of armature 52 and said armature, upper and lower right hand windings of the 105 repeating coil T, upper and lower conductors of the trunk line X, upper and lower left hand windings of the repeating coil T', armature 112 and its working contact, armature 119 and its working contact, and the lower winding of supervisory relay 109 to battery. Line relay 24 of repeater D and 110 supervisory relay 109 of repeater D' energize 115 in series over the above traced circuit. Supervisory relay 109, upon energizing, closes, at armature 133, a circuit extending from ground by way of release trunk conductor 194, working contact of armature 133 120 and said armature, and relay 110 to battery. Relay 110 upon energizing closes a locking circuit for itself at armature 137 and closes 125 a point in the circuit of reversing relay 103, at armature 135. The said reversing relay 130

however, does not energize at this time because its circuit is open at armature 132, of supervisory relay 109. The function of relay 110, in outgoing calls, is to hold the circuit of reversing relay 103 open so as to prevent its operation in case the trunk line X should be open. The utility of this operation will be explained more fully hereinafter.

- 10 In the repeater D, line relay 24, upon energizing, closes a circuit for the release relay 23 including armature 47 and its resting contact, and armature 41 and its working contact. Release relay 23, upon energizing, 15 places ground on conductor 91 thereby closing a circuit for the busy lamp L², whereupon the said lamp becomes illuminated to inform the operator in exchange No. 1 of the busy condition of the trunk line X. A 20 branch of this circuit extends to battery by way of the upper or polarizing winding of electropolarized relay 20, and still another branch extends to battery by way of the left hand or polarizing winding of electropolarized relay 79 of the operator's circuit O. The 25 two electropolarized relays 20 and 79, however, do not energize at this time for the reasons previously given for the electropolarized relays 174 and 111 in exchange No. 2. As a 30 further result of the energization of release relay 23, it completes the following bridge across conductors 93 and 95: from conductor 95, by way of the working contact of armature 39 and said armature, armature 55 and 35 its resting contact, lower left winding of repeating coil T, armature 54 and its resting contact, lower winding of electropolarized relay 20, resistance 57, resting contact of armature 53 and said armature, upper left 40 winding of repeating coil T, and working contact of armature 40, of line relay 24, and said armature, to conductor 93.

Upon referring to Fig. 3 it will be noted that the conductors 93-95, inclusive, normally extend to and terminate in the selector E. Accordingly, the line and release relays of the said selector immediately energize, responsive to the closure of the previous traced bridge across conductors 93 and 95, and upon so doing, they prepare the switch for operation in the usual manner. Electropolarized relay 20, however, of which the lower winding is included in the bridge across conductors 93 and 95, does not energize at this time because the current flowing in its lower winding is in such a direction as to oppose that flowing in its upper winding. As a result of the energization of the release relay of selector E, a ground potential is placed on release trunk conductor 94 thereby closing a circuit for the right hand or polarizing winding of electropolarized relay 78. Relay 78, however, being similar to relay 79 does not energize at this time.

65 The events which have taken place as a

result of the operation of key K⁴ may be briefly summed up thus. There is a guarding ground potential on the test contact 191 and its multiples in the banks of the switches in exchange No. 2, which have access to the 70 trunk line X; the busy lamp associated with the operator's circuit O and consequently with the trunk line X is lighted to inform the operator in exchange No. 2 that the said trunk is busy; and the incoming toll selector 75 E, which is associated with the trunk line X, is ready for operation.

The toll operator in exchange No. 2 now operates her calling device S' in accordance with the first digit of the desired number, 80 thereby interrupting the circuit of line relay 104 of repeater D' a corresponding number of times. Each time the line relay 104 de-energizes, due to these interruptions in its circuit, it opens the circuit of line relay 24 of repeater D and supervisory relay 109 of repeater D', and at armature 120 closes the 85 circuit of slow acting relay 106. Slow acting relay 106 is accordingly maintained energized throughout the series of interruptions 90 and, at armature 125, places the resistance 140 in multiple with the lower winding of supervisory relay 109 so as to afford a better 95 impulsive circuit for the line relay 24 of repeater D. Supervisory relay 109 may or 100 may not hold up during the series of interruptions, dependent upon its adjustment and a number of other factors. In the event that the said relay 109 follows the first impulse it 105 closes at armature 132, a point in the circuit of reversing relay 103. Relay 103, however, 110 is not energized at this time for the reason that relay 106, upon energizing, opens a point in the circuit of the said reversing relay 103, at armature 124. At the end of the 115 series of impulses, line relay 104 comes to rest in an energized condition and slow acting relay 106, upon deenergizing, removes the resistances 140 from in shunt of the lower 120 winding of supervisory relay 109, at armature 125; and, assuming that supervisory relay 109 has held its armatures in a retracted position during the series of impulses, closes the circuit of reversing relay 103 at armature 124. This relay, however, being inductively 125 sound and having a stiff adjustment, is not able to energize before its circuit is opened, at armature 132, by the subsequent energization of supervisory relay 109.

In the repeater D, line relay 24 deenergizes each time its circuit is opened by the deenergization of line relay 104 of repeater D' and, at armature 140, opens the circuit of the line relay of selector E (Fig. 3). As a further result of the deenergizations of line 125 relay 24 it maintains the slow acting relay 25 energized throughout the series of interruptions. Upon energizing, relay 25 closes the bridge across conductors 93 and 95 at armature 44 by a more direct path which ex- 130

cludes the lower winding of electropolarized relay 20, resistance 57, and the left hand windings of the repeating coil T. This is the usual expedient made use of in order to obtain first class switch control. As a result of the interruptions produced in the circuit of the line relay of selector E, the said switch raises its shaft and wipers step by step until they come to rest opposite the desired level of bank contacts and, upon the cessation of the series of interruptions, rotates the said wipers in search of an idle trunk line.

We shall assume in the present case that the digit that has been called is 1 and that the second selector F is the first one found to be idle and consequently is the one selected. The line and release relays of selector F now energize thus preparing the switch for operation and establishing a holding circuit of the selector E in the usual manner.

The toll operator in exchange No. 2 may now operate her calling device in accordance with the second digit of the desired number, whereupon selector F, in exchange No. 1, is caused to raise its shaft and wipers step by step until the latter stand opposite the desired level of bank contacts. In this case also, we shall assume that the digit called is 1, although it may be any other digit, and we shall assume further that the connector H is the switch selected. The line and release relays of the said connector now energize and prepare the switch for operation, at the same time closing a holding circuit for the switches E and F in the usual manner.

The operator may now manipulate her calling device in accordance with the third digit of the desired number, whereupon the connector H raises its shaft and wipers step by step until the latter stand opposite the desired level of bank contacts, being in this case the level in which the line of substation A' terminates.

The operator may now turn the dial of her calling device for the next and final digit of the desired number, whereupon the wipers of the connector H are rotated step by step until they finally come to rest upon the desired set of contacts, or the one in which the line of substation A' terminates. Assuming that the line of substation A' is idle, the connector H sends ringing current out intermittently to ring the bridged bell at the called substation.

The operator, having finished calling the number, returns her key K⁴ to normal position thereby shifting the bridge across conductors 193 and 195 so as to include the normally closed contacts controlled by spring 162, the right hand winding of electropolarized relay 174, impedance 173, and the normally closed contacts controlled by spring 161. The electropolarized relay 174 now

energizes because the current flowing in its right hand winding is in such a direction as to assist the current flowing in its left hand winding. Upon energizing, relay 174 closes, at armature 180, a circuit for supervisory lamp L⁴ and the said lamp accordingly becomes lighted.

When the subscriber at substation A' removes his receiver, in response to the ringing of his bell, the back bridge relay of the connector H energizes in the usual manner and reverses the incoming line conductors as regards their connection with the windings of the line relay of the said connector. In the repeater D electropolarized relay 20 now energizes in response to this reversal since its two windings, which heretofore have opposed each other, are now energized in such a way as to assist each other. Upon energizing, relay 20 closes a locking circuit for line relay 24, at armature 19; and, at armature 30, removes the upper winding of line relay 24 from the control circuit and substitutes the upper winding of supervisory relay 22 therefor. It will be noted that, since the upper winding of supervisory relay 22 is connected to the same pole of battery as the lower winding of supervisory relay 109, no current flows over the toll line X and consequently relay 22 does not energize and supervisory relay 109 deenergizes. Supervisory relay 109, upon deenergizing, completes the circuit of reversing relay 103, at armature 132, as follows: from ground by way of armature 123 and its working contact, armature 124 and its resting contact, resting contact of armature 132 and said armature, working contact of armature 135 and said armature, and reversing relay 103 to battery. Upon energizing, reversing relay 103 reverses, at armatures 117 and 118, the conductors leading to the upper and lower windings of line relay 104 as regards their connection with the said windings, thereby causing a reversal of current in conductors 193 and 195 and likewise in the bridge across these conductors in the operator's circuit O'.

Electropolarized relay 174 now retracts its armature 180, since the current flowing in each of its windings opposes the current flowing in the other, thereby extinguishing the supervisory lamp L⁴.

The operator, upon noting that the supervisory lamp L⁴ has become extinguished, knows that the called subscriber has answered and, accordingly, she throws the key K⁴ to listening position thereby placing her head set in bridge of the heavy talking conductors 193 and 195, at springs 164 and 165. The called subscriber and the toll operator may now converse with each other, the talking circuits, that are shown, being outlined by the heavy conductors. The toll operator tells the called subscriber to wait on the line

while she extends the connection to the subscriber who desires to converse with him.

The operator may leave her listening key thrown, if she so desires. In any event she 5 throws the key K^5 into calling position thereby operating the springs 166-168, inclusive. Spring 168, upon being operated, closes a circuit for release relay 176, in series with spring 171 of release key K^6 and 10 its resting contact. Upon energizing, release relay 176 prepares a locking circuit for itself, at armature 182; and, at armature 183, places ground on the operating conductor 198, by way of the following circuit: from ground, by way of the working contact of spring 167 and said spring, impulse springs of calling device S' , spring 166 and its working contact, and armature 183 and its working contact, to conductor 15 198. In the toll first selector E^5 , Fig. 3, the line and release relays immediately energize and prepare the switch for operation in the usual manner, and the latter places ground on the release trunk conductor 197 20 thereby closing a locking circuit for release relay 176 independent of spring 168 of key K^5 .

The operator may now turn the dial of the calling device S' in accordance with the 30 first digit of the desired number thereby interrupting the circuit of the line relay of selector E^5 a corresponding number of times. In response to these interruptions, the said line relay causes the said selector E^5 to raise 35 its shaft and wipers step by step until the latter stand opposite the desired level of bank contacts. At the end of the series of impulses the wipers of the said selector are rotated automatically to pick out an idle 40 trunk line terminating in the level of contacts opposite which they are raised. In the present case we shall assume that the wipers of switch E^5 are raised opposite the level in which the trunk line extending to toll second selector F^3 terminates and that 45 the said selector F^3 is the first one found idle and consequently the one selected.

The operator may now call the next digit, whereupon the selector F^3 responds by raising 50 its shaft and wipers until the latter stand opposite the desired level of contacts, which in this case we shall assume is the level in which the trunk line extending to the connector H' terminates. We shall assume further that, when the wipers of the 55 said selector are rotated at the end of the series of impulses to pick out an idle trunk line, the trunk line leading to the connector H' is the first one found idle and therefore is the one selected. The connector H' now 60 prepares itself for operation in the usual manner.

In response to the last two digits of the 65 called number, the connector H' is assumed to raise its wipers to the desired level and

rotate them until they finally come to rest on the set of contacts in which the line of substation A^3 terminates.

The operator, having called the desired number, throws her key K^5 to the opposite 70 or ringing position, thereby sending ringing current out over the established connection to the connector H' . Before describing the effect produced in the said connector, we shall consider the circuit changes caused 75 by springs 166-168, inclusive, returning to normal position. It will be noted that, with the spring 166 in normal position the operating conductor 198 is grounded by way of the marginal supervisory relay 175. It 80 may be stated that the operating conductor at this time extends to battery at the other end through a relay of comparatively low resistance, and accordingly supervisory relay 175 is energized immediately upon the 85 restoration of spring 166 to normal position thereby closing the circuit of supervisory lamp L^5 . Supervisory lamp L^5 is now lighted.

When the ringing current is projected out 90 over the established connection, as hereinbefore described, a ringing responsive relay is caused to energize with the final result that ringing current is sent out to ring the bridged bell at the called substation. When the ringing key is restored to normal position, the ringing responsive relay deenergizes with the final result that ringing current is removed from the called line. The operation may be repeated as many times as 95 100 necessary.

When the called subscriber answers, the battery feed relay, which is in the toll second or transmission selector, energizes with 105 the final result that the heavy talking conductors 196 and 199 are connected up so that they extend from the right hand end of the operator's circuit O' to the substation A^3 . As a further result of the energization of the battery feed relay, sufficient 110 resistance is inserted in the operating conductor 198 to cause the marginal supervisory relay 175 to deenergize and extinguish the lamp L^5 , thereby giving the operator 115 answering supervision.

The complete connection is now established 120 between the substation A^3 in exchange No. 2 and substation A' in exchange No. 1 and the subscribers thereat may converse as desired, the talking circuits, that are shown, being outlined by the heavy conductors.

When the conversation is completed the two 125 subscribers replace their receivers. When the receiver is replaced at substation A^3 , the beforementioned resistance, which was placed in the operating conductor 198 responsive to the answering of the subscriber at substation A^3 , is removed and the normal resistance is reintroduced therein, whereupon the marginal supervisory relay 175 130

energizes again and lights the supervisory lamp L^5 .

When the receiver is replaced at substation A' the back bridge relay of connector H deenergizes thereby reversing the current flow in the conductors 93 and 95 of the repeater D back to normal. Electropolarized relay 20 responds to the reversal of current by retracting its armatures. At armature 19, relay 20 opens the locking circuit of line relay 24 and, at armature 30 the said relay shifts the switch control circuit from battery, through the upper winding of relay 22, to ground by way of the upper winding 15 of line relay 24. Line relay 24 is now maintained energized in series with supervisory relay 109 of repeater D'. Supervisory relay 109, upon energizing, opens the circuit of reversing relay 103 at armature 132. 20 Upon deenergizing, reversing relay 103 reverses the current flow in the conductors 193 and 195 back to normal, whereupon electropolarized relay 174 attracts its armature and lights the supervisory lamp L^4 .

25 The toll operator, upon perceiving the lighted condition of lamps L^4 and L^5 , knows that the conversation is finished and that the subscribers have replaced their receivers. In order to release the connection to the subscriber at substation A', the operator momentarily operates the release key K^6 whereupon release relay 176 deenergizes and, at armature 182, opens its previously described locking circuit. As a further result 30 of the deenergization of relay 176, it opens the operating circuit at armature 183, whereupon supervisory relay 175 deenergizes and extinguishes the supervisory lamp L^5 . As a further result of the opening of the operating circuit, the established connection to the subscriber at substation A' is released and all the switches used therein are restored to normal position, in the usual manner.

45 In order to release the connection extending to the substation A', the operator momentarily operates the key K^3 , whereupon release relay 172 deenergizes; opens its locking circuit, at armature 179; and, at armatures 177 and 178, opens the bridge across line conductors 193 and 195 of the repeater D', in response to which electropolarized relay 174 falls back and extinguishes the supervisory lamp L^4 , and line relay 104 of repeater D' deenergizes. Upon deenergizing, line relay 104 opens the control circuit, at armature 119, whereupon line relay 24 of repeater D and supervisory relay 109 of repeater D' deenergize. As a further result 50 of the deenergization of line relay 104, it opens the circuit of release relay 105 and closes the circuit of slow acting relay 106, at armature 120. Release relay 105, upon deenergizing, opens the circuit of relay 106, at armature 122; and, at armature 123, re-

moves ground from the release trunk conductor 194. The busy lamp L^2 now becomes extinguished and the repeater D' and consequently the trunk line X is caused to test idle to the selectors having access to it in exchange No. 2. 70

In the meantime the repeater D and its associated selector E, together with the switches F and H, in exchange No. 1, have restored themselves to normal condition as will now be explained. Line relay 24, upon deenergizing responsive to the opening of the control circuit, as previously pointed out, opens the circuit of release relay 23 and closes the circuit of slow acting relay 25, at armature 41; and, at armature 24, opens the bridge across conductors 93 and 95 whereupon the switches E, F and H restore themselves to normal position in the usual manner. Release relay 23, upon deenergizing, opens the circuit of relay 25, at armature 38, and removes ground from conductor 91, at armature 37, thereby extinguishing the busy lamp L^2 . All the apparatus used in extending the previously described connection is now restored to normal condition. 90

Assuming now that the subscriber at substation A' fails to replace his receiver at the end of the conversation, the parts of the releasing operation that differ from these already explained will be pointed out. Since the current flow in the trunk line X ceases entirely upon the answering of the subscriber at substation A', it is easily seen that under these conditions, the mere opening 95 of the control circuit does not affect the repeater D on the distant end of the toll line. Consequently if other means were not provided for releasing the connection, the toll line X would remain tied up. 100

Assuming that the operator initiates the release of the connection, with the receiver still off at substation A, the repeater D' opens the control circuit and assumes normal condition without having effected any change in the repeater D. Immediately after repeater D' assumes normal condition, however, line relay 107 energizes in series with supervisory relay 22 of repeater D over the following circuit: from ground by way of 110 the upper winding of line relay 107, resting contact of armature 136 and said armature, resting contact of armature 138 and said armature, resting contact of armature 112 and said armature, and thence by way 115 of a previously traced circuit to battery, through the upper winding of supervisory relay 22. Line relay 107, upon energizing, closes a circuit for release relay 108, at armature 128. Upon energizing, release relay 108 places ground on release trunk conductor 194, at armature 129, thereby causing the repeater D', and consequently the toll line X, to test busy to the automatic switches having access to it, and lighting the busy 120 125 130

lamp L^3 again. As a further result of the operation of release relay 108, a bridge is completed across line conductors 100 and 101 thereby making the selector E^3 (Fig. 3) ready for operation in the usual manner.

- 5 In the repeater D, supervisory relay 22, upon energizing, closes the circuit of relay 21, at armature 35, and opens the locking circuit of line relay 24, at armature 36.
- 10 Relay 21, upon energizing, opens a point in the circuit of the upper winding of line relay 24, at armature 32, and locks itself to grounded conductor 91, at armature 33.
- 15 Line relay 24, upon deenergizing, opens the bridge across conductors 93 and 95, at armature 40, and opens the circuit of release relay 23, at armature 41. In response to the opening of the bridge across conductors 93 and 95, at armature 40, electropolarized relay 20, which is adjusted so as not to hold up with only its polarizing winding energized, falls back and, at armature 19, opens a point in the circuit of the lower winding of line relay 24 and, at armature 30, opens
- 20 the control circuit, whereupon supervisory relay 22 of repeater D and line relay 107 of repeater D' deenergize. Supervisory relay 22, upon deenergizing, opens the initial circuit of relay 21, at armature 35, but the said relay 21 is maintained energized by means of its previously mentioned locking circuit. With relay 21 energized it will be noted that the circuit of the upper winding of line relay 24 is held open, at armature 32, and consequently any capacity discharge through the upper winding of line relay 24 from the toll line X, due to the control circuit being shifted suddenly from battery to ground by armature 30 of relay 20, is avoided. Release relay 23 now deenergizes in response to the opening of its circuit, at armature 41 of line relay 24, and removes the ground potential from conductor 91, at armature 37, whereupon relay 21 deenergizes and, at armature 32, extends the control circuit to ground by way of the upper winding of line relay 24. The time required by the slow acting release relay 23 to fall back gives ample time for any discharge that might result from switching the control circuit from battery to ground, to pass to ground through the upper winding of line relay 107 of the repeater D'.
- 25 It has been found that if the above mentioned precaution is not taken, line relay 24 is kicked up again, followed by the energization of relay 20 which switches the control circuit back to battery again, and the operation is repeated over and over.
- 30 In regard to the switches E, F, and H, it may be stated that they all release in response to the opening of the bridge across conductors 93 and 95 at armature 40 of line relay 24.
- 35 In the repeater D', as a result of the de-

energization of line relay 107, the said repeater and its associated selector assume normal condition.

We shall now assume that the subscriber at substation A in exchange No. 1 desires to call the subscriber at substation A² in exchange No. 2. In order to do this, he calls the toll recording operator in the usual manner and the toll recording operator makes out a ticket or in some other way passes the information she obtains over to the toll operator in exchange No. 1.

In order to call the subscriber at substation A² in exchange No. 2, the toll operator in exchange No. 1, assuming that the toll line X is idle as indicated by the unlighted condition of the lamp L^2 , may throw the key K^2 to the call out position, thereby operating the springs 73-75, inclusive. Spring 75, upon being operated, closes a circuit for release relay 80 in series with spring 76, of release key K^3 , and its resting contact. Upon energizing, release relay 80 places ground on conductor 91, at armature 88, thereby preparing a locking circuit for itself and closing an energizing circuit for busy lamp L^2 . This ground potential extends to the polarizing winding of the electropolarized relays 79 and 20 but these relays are not energized by their polarizing windings alone because of hereinbefore given reasons. As a further result of the energization of release relay 80, it places the following bridge across conductors 90 and 92: from conductor 92, by way of the working contact of armature 87 and said armature, working contact of spring 74 and said spring, impulse springs of the calling device S, the resistance associated with the left hand or secondary winding of the operator's induction coil, the said winding, spring 73 and its working contact, and armature 88 and its working contact, to conductor 90.

In the repeater D, as a result of the placing of ground upon conductor 91, a circuit is closed from ground by way of conductor 91, armature 37 and its resting contact, and relay 29 to battery. Upon energizing, relay 29 opens the normally closed bridge across the conductors 90 and 92, at armatures 53 and 54, and, at the working contacts of the said armature, places the upper and lower windings of line relay 27 in bridge of the said conductors, the bridge in either case including the upper and lower left windings of the repeating coil T. Line relay 27 now energizes, over the previously traced bridge across conductors 90 and 92 in the operator's circuit O, and closes a circuit for release relay 26, at armature 49. Upon energizing, release relay 26 prepares a circuit for slow acting relay 25, at armature 46, and places a multiple ground on conductor 91, at armature 47. It will be noted

that release relay 80 is now locked up to conductor 91, at armature 88, in series with spring 76, of release key K^3 , and its resting contact. As a further result of the energization of line relay 27, it closes, at armature 48, the following circuit: from ground by way of the upper winding of line relay 107 of repeater D' , resting contact of armature 136 and said armature, resting contact 10 of armature 138 and said armature, resting contact of armature 112 and said armature, upper and lower left hand windings of repeating coil T' , upper and lower conductors of trunk line X , upper and lower right hand 15 windings of repeating coil T , armature 52 and its working contact, armature 48 and its working contact, and the lower winding of supervisory relay 22 to battery. Supervisory relay 22, of repeater D and line relay 20 107 of repeater D' now energize in series over the above traced circuit. Supervisory relay 22, upon energizing, opens a point in the circuit of reversing relay 28, at armature 34, and closes a circuit for relay 21, at armature 35. Upon energizing, relay 21, which corresponds to relay 110 of repeater D' , closes a locking circuit for itself at armature 33, and prepares a circuit for reversing relay 28, at armature 31.

30 In the repeater D' line relay 107, upon energizing, in series with supervisory relay 22 of repeater D , closes the circuit of release relay 108, at armature 128. Upon energizing, release relay 108 prepares a circuit for slow acting relay 106, at armature 130, and places ground on release trunk conductor 194, at armature 129. This ground-potential extends to the test contact 191 and its multiples in the banks of the automatic 35 switches having access to the toll line X , thereby guarding the said line against intrusion in the usual manner. A branch of this circuit extends to the busy lamp L^3 which becomes lighted, thereby informing 40 the toll operator of the busy condition of the toll line. It will be noted that the polarizing windings of the polarized relay 174 of the operator's circuit O and polarized relay 111 of the repeater D' , are energized at 45 this time, but as before stated neither of the said relays is operated by current flowing in the polarizing winding alone. As a further result of the energization of release relay 108, it completes, at armature 131, the 50 following bridge across the conductors 100 and 101: from conductor 101, by way of the working contact of armature 131 and said armature, armature 116 and its resting contact, lower right winding of repeating coil T' , armature 114 and its resting contact, lower winding of electropolarized relay 111, resistance 141, resting contact of armature 113 and said armature, upper right winding of repeating coil T' , and the working 55 contact of armature 127 and said armature,

to conductor 100. In response to the closure of this bridge across the conductors 100 and 101, the line and release relays of the incoming toll first selector E^3 , Fig. 3, are energized in the usual manner thereby preparing the switch for operation. Electropolarized relay 111, however, is not energized at this time because the current flowing in either of its windings opposes that flowing in the other. 75

It will be seen now that the busy lamps L^2 and L^3 on either end of the toll line X are lighted; the said toll line is made busy to the automatic switches having access to it; and the incoming toll selector E^3 , associated with the toll line X in exchange No. 2, is made ready for operation, as result of the throwing key K^2 in the operator's circuit O in exchange No. 1, to the call out position. 85

The calling operator may now manipulate her calling device S in accordance with the proper digits, whereupon the selectors E^3 and F' and the connector H' are operated in the usual manner to extend the connection 90 to the line of substation A^2 . In this case the connector H' which is a combination toll and regular connector has only the operating characteristics of a regular connector, such as connector H , and accordingly ringing current is intermittently sent out to ring the bridged bell at the called substation in the usual manner. 95

In regard to the operation of the repeaters D and D' in repeating the impulses to 100 the automatic switches in exchange No. 2, it may be said that the action is exactly the same in this call as in the one previously described, with the obvious exception that the repeaters occupy reversed positions 105 owing to the fact that the call is coming in to exchange No. 2 from exchange No. 1, in this case.

The calling operator, having finished 110 calling the number, may restore the key K^2 to normal position and wait for the subscriber at substation A^2 to answer. When the key K^2 is restored to normal position the original energizing circuit of release relay 112 is broken at spring 75, but the said relay is maintained energized over its previously 115 mentioned locking circuit. Springs 73 and 74, in returning to normal position, shift the bridge across conductors 90 and 92 so as to include only the working contact of 120 spring 87 and said spring, normally closed contacts controlled by spring 74, left hand winding of electropolarized relay 79, impedance 60, normally closed contacts controlled by spring 73, and armature 86 and its working contact. Electropolarized relay 79 operates at this time, because its two windings 125 assist each other and closes, at armature 85, the circuit of supervisory lamp L' whereupon the said lamp becomes lighted. 130

When the subscriber at substation A² responds to the ringing of his bell, by removing his receiver, the ring cut off relay in the connector H' is operated to cut off the ringing current and connect up the back bridge relay in the said connector. When this is done the back bridge relay in the connector H' energizes and reverses the current flow in the line conductors extending to the connector H' and consequently in the conductors 100 and 101 extending back to the repeater D'. Electropolarized relay 111, the lower winding of which is included in a bridge across these conductors in the repeater D', now energizes because its two windings, which heretofore have opposed each other, are now energized in the same direction. Upon energizing, relay 111 closes a locking circuit for line relay 107, at armature 139, and shifts the switch control circuit, at armature 138, from ground, by way of the upper winding of line relay 107, to battery, by way of the upper winding of supervisory relay 109. Since both ends of the control circuit are now connected to the same pole of battery, supervisory relay 109 of repeater D' is not energized at this time and supervisory relay 22 of repeater D deenergizes. Upon deenergizing, supervisory relay 22 closes the circuit of reversing relay 28, at armature 34. Upon energizing, reversing relay 28 reverses the conductors 90 and 92 as regards their connection with the windings of line relay 27, at armatures 50 and 51. In response to this reversal, electropolarized relay 79 retracts its armature 85, thereby extinguishing the lamp L' to give the operator answering supervision. The operator, upon noting that the lamp L' has become extinguished, knows that the called subscriber has answered and she accordingly throws the key K' to the listening position thereby operating springs 71 and 72 which connect her head set in bridge of the heavy talking conductors. She now converses with the subscriber at substation A² and tells him to wait on the line while she calls the subscriber that desires to converse with him.

In order to call the subscriber at substation A the calling operator throws her key K' to the calling position thereby operating the springs 68-70 inclusive. Spring 70, upon being operated, closes a circuit for release relay 77 in series with spring 89 of release key K, and its resting contact. Release relay 77, upon energizing, prepares a locking circuit for itself, at armature 83, and, at armatures 81 and 82, completes the following bridge across line conductors 93 and 95: from line conductor 95, by way of spring 67 and its resting contact, working contact of armature 82 and said armature, working contact of spring 69 and said spring, impulse springs of the calling device S, the secondary winding of the operator's induction coil,

together with the associated resistance, spring 68 and its working contact, armature 81 and its working contact, and the resting contact of spring 66 and said spring, to conductor 93. In response to the closure of this bridge, the line and release relays of selector E, Fig. 3, energize; prepare the switch for operation; and place ground on release trunk conductor 94 in the usual manner. The placing of a ground release trunk conductor 94 by the release relay of the said selector E establishes a locking circuit for release relay 77, in series with the working contact of armature 83 and said armature, and the release key K, independent of spring 70 of key K'.

The calling operator may now manipulate her calling device in accordance with the digits of the desired number whereupon the selectors E and F and the connector H are operated to give access to the line of substation A. The connector H now sends ringing current out intermittently to ring the bridged bell at the called substation.

Having finished dialling the number, the operator restores the key K' to normal position, thereby removing her head set and associated calling device from the bridge across conductors 93 and 95 and inserting the impedance 61 and the right hand winding of electropolarized relay 78 therein. The current is now flowing through the two windings of relay 78 in the same direction and accordingly the armature 64 is operated and the supervisory lamp L becomes lighted.

When the subscriber at substation A responds to the ringing of his bell by removing his receiver, the connector H reverses the direction of current flow in the established connection, and consequently in conductors 93 and 95 and the bridge across the said conductors in the operator's circuit O. Electropolarized relay 78 now retracts its armature, thereby extinguishing the lamp L so as to give the operator answering supervision. The two subscribers may now converse with each other as desired.

After the conversation is finished the two subscribers replace their receivers. When the receiver is replaced at substation A the consequent reversal of current flow causes the electropolarized relay 78 in the operator's circuit O to reoperate its armature 84 and light the lamp L, whereupon the operator releases the connection by momentarily operating the release key K.

When the receiver is replaced at substation A² the consequent reversal of current flow causes the electropolarized relay 111 to retract its armatures, thereby opening the locking circuit of line relay 108, at armature 139, and closing at armature 138, the initial circuit of the line relay 107, in series with the supervisory relay 22 of repeater D. Line relay 107 is now maintained energized over

- this circuit and supervisory relay 22 energizes. As a result of the energization of supervisory relay 22, the circuit of reversing relay 28 is opened at armature 34. Relay 28, upon deenergizing, reverses the direction of current flow in the conductors 90 and 92 to normal, whereupon electropolarized relay 79 attracts its armature, thereby lighting the supervisory lamp L^2 .
10. In order to release the connection, the operator momentarily operates the release key K^3 whereupon the release relay 80 deenergizes; opens its locking circuit at armature 88; and, at armatures 86 and 87, opens the bridge across conductors 90 and 92, with the result that the line relay 27 deenergizes; opens the control circuit, at armature 48; and at armature 49 opens the circuit of release relay 26. Upon deenergizing, release relay 26 removes ground from conductor 91, and busy lamp L^2 accordingly becomes extinguished and all the relays of repeater D that have not already done so assume normal position. As a result of the opening of the control circuit by line relay 27, line relay 107 of repeater D' deenergizes; opens the circuit of release relay 108, at armature 128; and, at armature 127, opens the bridge across conductors 100 and 101. The switches E^3 F' and H' now restore themselves to normal position in the usual manner. Release relay 108, upon deenergizing, removes ground from release trunk conductor 194, at armature 121, whereupon the busy lamp L^3 becomes extinguished and all the relays of repeater D' that have not already done so assume normal position. The entire connection is now released and all the apparatus used is restored to normal position.
40. If we assume that the subscriber at substation A in the connection just described had desired to obtain connection with some subscriber in exchange No. 3, (Fig. 3) the operations performed by the calling operator would differ only in that she calls two extra digits which are the ones which give access to exchange No. 3. Assuming that the operator in exchange No. 1 is extending a connection to a subscriber in exchange No. 3 by way of the trunk line X, and that she has already thrown her call out key, with the result that the repeaters D and D' and the selector E^3 are made ready for operation, she operates her calling device in accordance with the digit 0, whereupon the selector E^3 raises its wipers to the tenth level and rotates them in search of an idle trunk line. We shall assume that the trunk line extending to the toll switching selector F^2 is the first one found idle and consequently the one selected. That being the case, when the operator operates her calling device for the second digit in the desired number, which in this case is the digit 1, the selector F^2 raises its shaft and wipers until the latter stand opposite the first level of bank contacts and automatically rotates them in search of an idle trunk line. Assuming now that the trunk line extending to the repeater D^2 is the first one found idle and consequently the one selected, the wipers of selector F^2 will establish connection with a set of bank contacts associated with repeater D^2 which is similar to the set comprising contacts 190, 191, and 192, associated with repeater D, and the repeater D^2 will operate the same as the repeater D' did when the operator in exchange No. 2 threw the key K^4 to the call out position. Consequently, the repeater D^2 places ground on its associated release trunk conductor, thereby lighting the busy lamp in the operator's circuit O^2 , and at the same time places battery on the trunk line Z through its supervisory relay so as to operate the line relay of the repeater D^2 . The line relay of the repeater D^2 now energizes and closes a circuit for the release relay which, upon energizing, lights the busy lamp associated with the operator's circuit O^3 so as to inform the operator in exchange No. 3 of busy condition of the trunk line Z. The repeater D^2 also closes a bridge across the line conductors of the trunk line extending to the incoming toll selector E^8 , at this time, and consequently the said selector is made ready for operation in the usual manner. The calling operator now manipulates her calling device in accordance with the remaining digits of the desired number whereupon the selectors E^8 and F^4 and the connector H^2 are operated to give access to the called line in the usual manner.
- When the called subscriber answers, the resulting reversal of current flow causes the electropolarized relay in repeater D^3 to function, with the result that the supervisory relay connected in the control circuit in the repeater D^2 is caused to deenergize, resulting in a reversal of the direction of the current flowing in the trunk line leading to the repeater D^2 and consequently in the conductors 100 and 101 of the repeater D'. It is easily seen that from this point the operation continues in exactly the same manner as it did when the called subscriber was in exchange No. 2.
- It will be noticed that no provisions have been made for signalling back and forth between the toll operators in the different exchanges by ringing. This result, however, is accomplished in the present toll trunking system in a different manner. Upon referring to Fig. 3, three dotted rectangles 10, 11, and 12, will be seen. Each of these rectangles is supposed to represent certain equipment at the operator's position that is used in answering a call extended to her by a toll operator in some other exchange. It is shown only diagrammatically in Fig. 3 but in fact is similar to the equipment referred to in Fig. 3.

to by the reference character J in Fig. 3 of the drawings accompanying the patent to Willis, hereinbefore referred to. To illustrate just how this is done we shall assume that the toll operator in exchange No. 1 wishes to obtain some information from the toll operator in exchange No. 2. To do this the calling operator dials the number 00 whereupon the selectors E³ and F² are operated to give access to a trunk line extending to the operator's position and terminating in the dotted rectangle 11. When this is done the associated lamp is lighted. The operator, upon seeing the lighted lamp, throws her key, thereby extinguishing the lamp and connecting her head set with the trunk line. Similarly the operator in exchange No. 1 may extend a connection to the operator in exchange No. 3, by dialling the number 010 whereupon the selectors E³, F² and E⁸, are operated to give access to a trunk line extending to the operator's equipment, designated by the reference character 12 in exchange No. 3. Obviously the operator in exchange No. 2 may extend a connection to an operator in either exchange No. 1 or exchange No. 3 by dialling the digit 0. It is also equally evident that the operator in exchange No. 3 may extend a connection to the operator in exchange No. 2 by dialling the No. 00 or that she may extend a connection to the operator in exchange No. 1 by dialling the number 010.

A brief description, of the method used by a night operator in exchange No. 2 in handling calls, will now be given. Assuming that the traffic over the toll lines terminating in exchange No. 2 is not more than can be handled by two toll operators, only two positions, obviously, will be required in said exchange and one operator can easily take care of the small amount of traffic which is usual at night, by presiding over the two positions. In the case, however, that there are a great number of positions in exchange No. 2 an operator cannot reach all the toll lines from any one position. In this event it becomes necessary to provide means whereby she may extend a connection to any toll line from a given point. In keeping with the spirit of the invention, a number of link circuits (not shown) have been provided. Each link is substantially the same as the operator's circuit O' with the exception that one end is connected directly with a toll switching selector such as toll switching selector F², instead of being connected with a repeater such as the repeater D'.

When an operator who is provided with these before mentioned link circuits wishes to extend a connection over any toll line which is terminated in the banks of the before mentioned toll switching selector, she dials the proper digit, thereby causing the switching

selector to raise its wipers to the desired 65 level and rotate them to pick out an idle toll line. From this point the operation continues in the usual manner.

After having extended the connection to the distant subscriber the operator extends 70 the connection to the subscriber whose line terminates in the same exchange by way of the toll service trunking system in the usual manner.

Referring now to relay 21 of repeater D, 75 and relay 110 of repeater D', the function of either of these relays in connection with an outgoing call will be explained more in detail. It often happens that when toll lines, such as the toll line X, connect two small exchanges, the toll operator is dispensed with and the subscribers themselves are given access to the toll lines and are allowed to dial 80 their own connections from one exchange to the other, and in order to make the proper charges, each line may be equipped with a meter that operates in response to a reversal 85 of current which takes place when the called subscriber answers. If the repeaters, such as the repeaters D and D', were used in such a 90 system without being equipped with relays, such as the relays 21 and 110, and if the associated trunk line, such as the trunk line X, were open when a subscriber makes a call the supervisory relay on the calling end of the 95 trunk line would not be energized and the reversing relay, such as the reversing relay 28 of repeater D or reversing relay 103 of repeater D', would operate immediately and cause the current flow in the calling line to be 100 reversed in the same manner as when a call is answered. This would obviously operate the calling subscriber's meter, thereby charging him for a connection which he did not obtain. Taking the repeater D' for example, when the said repeater is equipped with a relay such as the relay 110, it is impossible for an open interexchange trunk line to cause a reversal of current in the calling line owing 105 to the fact that the circuit of the reversing relay 103 is held open at armature 135 until relay 110 energizes, which it cannot do if the 110 trunk line X is open.

Having fully described and ascertained the features of the invention, what is considered to be new and desired to have protected by Letters Patent will be pointed out in the appended claims.

What I claim is:

1. In an automatic telephone exchange 120 system, a toll line incoming from another exchange, a local trunk line normally disconnected from said toll line, operator controlled switching means for connecting said local trunk with local subscribers' lines, and an 125 operator's link circuit for connecting said toll line and local trunk to establish toll connections, said link circuit being indi-

vidual to and permanently associated with both the said toll line and the said local trunk line.

2. In an automatic telephone exchange system, a toll line incoming from another exchange, a local trunk line, automatic switches for connecting said local trunk with local subscribers' lines, an operator's link circuit associated with and individual to both the 10 said toll line and the said local trunk for connecting the two together, operator's equipment associated with said link circuit for use in establishing toll connections, and a toll repeater connected in multiple with said link 15 circuit, whereby said switches may be controlled over said toll line independent of said link circuit.

3. In an automatic telephone exchange system, a group of toll lines incoming from another exchange, a toll switchboard whereat 20 said toll lines terminate, an equivalent group of local trunks terminating at said switchboard, a plurality of operators' link circuits connecting said toll lines and local trunks, 25 whereby each local trunk is made individual to a particular toll line, a plurality of repeaters connected to said toll line in multiple with said link circuits, separate sets of talking conductors extending through said 30 link circuits and repeaters, automatic switches for extending said local trunks to local subscribers' lines to establish toll connections, and circuits whereby said switches may be controlled either from said link 35 circuits or from said repeaters.

4. In an automatic telephone exchange system, a group of toll lines incoming from another exchange, a toll switchboard whereat 40 said toll lines terminate, an equivalent group of local trunks terminating at said switchboard, a plurality of operators' link circuits connecting said toll lines and local trunks, whereby each local trunk is made individual to a particular toll line, automatic 45 switches for extending said local trunks to local subscribers' lines to establish toll connections, operator's equipment associated with said link circuits for controlling said switches, and other means for controlling 50 said switches to establish connections independent of said link circuits.

5. In an automatic telephone exchange system, a group of toll lines incoming from another exchange, a toll switchboard whereat 55 said toll lines terminate, an equivalent group of local trunks terminating at said switchboard, a plurality of operators' link circuits connecting said toll lines and local trunks, whereby each local trunk is made individual 60 to a particular toll line, automatic switches for extending said local trunks to local subscribers' lines to establish toll connections, and operator's talking, ringing, switch controlling, and supervisory equipment associated with said link circuits.

6. In an automatic telephone exchange system, a toll line incoming from another exchange and extending through an automatic impulse repeater to an automatic switch, an operator's link circuit bridged 70 around said repeater, and means for connecting the said toll line with said switch for connecting purposes either by way of said repeater or by way of said link circuit.

7. In an automatic telephone exchange 75 system, a toll line incoming from another exchange, two automatic switches permanently associated with said toll line and individual thereto, an automatic impulse repeater and an operator's link circuit, both 80 of which are permanently associated with and individual to said toll line, means for connecting said toll line with one of said switches by way of said repeater, and means for connecting the said toll line with the 85 other switch by way of said link circuit.

8. In a telephone system, a trunk line connecting two exchanges, means operated when the trunk line is taken for use at the first exchange for establishing a ground return 90 control circuit over said trunk line, automatic switches at the second exchange controlled over said control circuit to establish connection with a called subscriber's line, a reversing relay in the first exchange, means actuated when the called subscriber answers for stopping the flow of current in said control circuit to control said relay, and a second relay and circuit connections therefor effective to prevent said reversing relay from 95 being affected in case said trunk line is open when the same is taken for use.

9. In a telephone system, a trunk line, an automatic impulse repeater included in said trunk line, two branches connected to said trunk line on opposite sides of said repeater, and an operator's link circuit individual to 105 said trunk line for connecting said branches.

10. In a telephone system, a trunk line comprising two normally disconnected sections, an automatic repeater at the junction of said sections for repeating impulses from one section to another, a branch connected to each section, and an operator's link circuit individual to said trunk line for connecting 110 said branches.

11. In a telephone system, an automatic impulse repeater, a trunk line comprising 115 two talking conductors extending through said repeater, two talking branches connected to said talking conductors, on opposite sides of said repeater, and an operator's link circuit comprising talking conductors for connecting said branches, said link circuit being individual to said branches.

12. In a telephone exchange system, an automatic switch, a trunk line incoming to the exchange, two parallel talking circuits permanently connected to said switch at one end and to said trunk line at the other end, 120 130

- operator's manual equipment associated with one talking circuit, and automatic switch control equipment associated with the other talking circuit.
- 5 13. In a telephone system, a trunk line, an automatic switch individual to said trunk line, an operator's link circuit individual to said trunk line and said switch for connecting them together to establish talking connections, and means for setting up other talking connections over said trunk line in either direction, said talking connections excluding said link circuit. 70
- 10 14. In a telephone system, a calling office and a called office, a trunk line connecting said offices, an electro-responsive device in the calling office, a relay in the calling office, means in the calling office for closing an energizing circuit for said relay including a conductor of said trunk line, a second relay energized responsive to the operation of the first relay, means in the called office for de-energizing said first relay, and a circuit for said device closed responsive to the first relay being deenergized when the second relay is energized. 80
- 15 15. In a telephone system, a control circuit extending to a distant point, a primary supervisory relay included in said control circuit, means for energizing said primary supervisory relay by closing said control circuit at the near end thereof, a circuit-preparing relay operated responsive to the energization of said primary supervisory relay, means at the distant end of said control circuit for opening the same to deenergize said primary supervisory relay, a secondary supervisory relay, and a circuit for said secondary supervisory relay including contacts closed by said primary supervisory relay when it is deenergized and contacts closed by said circuit-preparing relay when it is energized. 90
- 20 16. In a telephone system, a control circuit extending to a distant point, a primary supervisory relay included in said control circuit, means for energizing said primary supervisory relay by closing said control circuit at the near end thereof, a circuit-preparing relay operated responsive to the energization of said primary supervisory relay, means at the distant end of said control circuit for opening the same to deenergize said primary supervisory relay, a secondary supervisory relay, a circuit for said secondary supervisory relay including contacts closed by said primary supervisory relay when it is deenergized and contacts closed by said circuit-preparing relay when it is energized. 95
- 25 17. In a telephone system, a first exchange and a second exchange, a trunk line connecting said exchanges, a control circuit including a conductor of said trunk line, alternate branches for said control conductor at the second exchange maintained at different potentials, two relays connected in said branches, respectively, means at the first exchange for placing a potential on said control conductor to bring about the operation of the relay in the connected branch at the second exchange, means responsive to the operation of the last named relay for opening a point in the disconnected branch, for shifting the control conductor to the alternate branch, and for subsequently closing the open point in the last named branch. 100
- 30 18. In a telephone system, a control conductor having alternate branches, a relay associated with each branch, said control conductor being connected to the first branch, means controlled over said control conductor from the distant end for operating the relay associated with the first branch, means responsive to the operation of said relay for disabling the relay in the second branch from operating, for shifting the said conductor from the first branch to the second branch, and for subsequently enabling the relay in the second branch to operate again. 105
- 35 19. In a telephone system, a trunk line, two branches for said trunk line, means controlled over said trunk line and one of its branches for setting up a talking connection extending to a called line and including said trunk line and said one branch, and controlled in another case over the other branch independent of said trunk line and said one branch for setting up a talking connection extending to the same called line and including said trunk line and said other branch. 110
- 40 20. In a telephone system, a trunk line having two branches at one end, means for connecting a calling line to said trunk line at the distant end, means including an automatic switch for extending a connection from said line to a called line by way of one of said branches, and means including said automatic switch for extending a connection from said line to the same called line by way of the other of said branches. 115
- 45 21. In a telephone system, a line, two branches for said line, means including an automatic switch having a wiper individual to said trunk line and common to said branches for setting up a connection from said line to the same called line over either of said branches. 120
- 50 22. In a telephone system, a trunk line divided into two sections, parallel talking branches connecting such sections, and individual to one section, and means controlled over either branch for setting up a talking connection including in serial relation both sections of said trunk line and the 125
- 55 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

branch over which such means is controlled.

23. In a telephone system, a trunk line divided into two sections, two parallel intermediate sections connecting the first mentioned sections and individual to said trunk line, and means for setting up a talking connection including both of the first named sections of said trunk line and either one of the intermediate sections in serial relation, said means being controlled in either case over the branch through which the connection is set up.

24. In a telephone system, a trunk line connecting two exchanges, a manual switchboard in the second exchange, a branch of said trunk line in the second exchange extending to an automatic switch individual to said trunk line, and a second branch individual to said trunk line and extending to said switch via said manual switchboard.

25. In a telephone system, a tail to tail connection between two automatic switches including an operator's link circuit, two locking seizing relays in said link associated with said switches, respectively, and two non-locking keys for unlocking said relays respectively.

26. In a telephone system, an operator's link circuit, automatic switching mechanism for extending a connection therefrom to a called line, a switch control circuit including a conductor of said link circuit, a self locking relay controlling a normally open point in said link circuit, a calling device common to said link and other similar links, a key individual to said link for connecting said calling device in said control circuit and for energizing said self locking relay, and a non-locking key for subsequently unlocking said relay.

27. In a telephone system, a trunk line divided into two sections, parallel talking branches connecting such sections and individual to one section, and automatic switching mechanism controlled over either talking branch for setting up a telephone connection including both trunk line sections.

28. In a combined automatic and manual telephone system, a trunk line divided into two sections, two parallel intermediate sections connecting the first mentioned sections and individual to said trunk line, and switch control means in each of said intermediate sections.

29. In a combined automatic and manual telephone system, a trunk line divided into two sections, two parallel intermediate sections connecting the first mentioned sections, and supervisory means in each of said intermediate sections.

30. In a combined automatic and manual telephone system, a trunk line divided into two sections, two parallel intermediate sections connecting the first mentioned sections and individual to said trunk line, one of said

intermediate sections including an automatic impulse repeater and the other intermediate section including an operator-controlled link circuit.

31. In a combined automatic and manual telephone system, a trunk line divided into two sections, two parallel intermediate sections connecting the first mentioned sections and individual to said trunk line, an operator's calling device, and means for connecting said calling device to one of said sections.

32. In a combined automatic and manual telephone system, a trunk line divided into two sections, two parallel intermediate sections connecting the first mentioned sections and individual to said trunk line, one of said intermediate sections being divided into two sections, an operator's calling device, and means for connecting said calling device with either section of said divided intermediate section.

33. In a combined automatic and manual telephone system, a trunk line divided into two sections, two parallel intermediate sections connecting the first mentioned sections and individual to said trunk line, an operator's calling device, means for connecting said calling device to one of said sections, and means in the other intermediate section for repeating to said trunk line impulses produced by said calling device.

34. In a telephone system, a trunk line incoming to a telephone exchange, two branches for said trunk line in said exchange, an automatic impulse repeater in one branch arranged to repeat impulses received over said trunk line, and an operator's link circuit in the other branch individual to said trunk line.

35. In a telephone system, a trunk line incoming to a telephone exchange, two branches connected to said trunk line, automatic switching mechanism in said exchange operable over one branch, and an operator's link circuit in the other branch individual to said trunk line.

36. In a telephone system, a trunk line incoming to a telephone exchange, two branches connected to said trunk line, automatic switching mechanism in said exchange operable over one branch, an operator's link circuit in the other branch individual to said trunk line, and switch-controlling means associated with said link circuit.

37. In a telephone system, a trunk line incoming to a telephone exchange, two branches extending from said trunk line, a toll service trunking system in said exchange, a separate trunking system in said exchange, one branch of said trunk line being extended to a first order switch in said toll service trunking system, and the other branch of said trunk being extended to a first order switch in the other trunking system.

38. In a telephone system, a trunk line incoming to a telephone exchange, two branches extending from said trunk lines, a toll service trunking system in said exchange, a separate trunking system in said exchange, one branch of said trunk line being extended to a first order switch in said toll service trunking system, the other branch of said trunk being extended to a first order switch in the other trunking system, and an ¹⁰ operator's link circuit inserted in and individual to the branch extending to the first order toll service switch.

In witness whereof, I hereunto subscribe my name this 30th day of June, A. D. 1921.

JOHN WICKS.
